UNITED STATES PATENT OFFICE.

PHILIP VIVIANO, OF ST. LOUIS, MISSOURI.

ADVERTISING SCALE.

Application filed May 9, 1925. Serial No. 29,115.

To all whom it may concern:

Be it known that I, PHILIP VIVIANO, a citizen of the United States, residing at St. Louis, in the county of St. Louis and State 5 of Missouri, have invented certain new and useful Improvements in an Advertising Scale, of which the following is a specification.

This invention relates to an improved 10 weighing scale together with the novel advertising means which is associated therewith.

Briefly, the invention has reference to a weighing scale which embodies a housing 15 provided in its front with a window through which advertisements upon an endless band are displayed successively in a step-by-step manner, each time the platform of the scale is occupied by a person.

One feature of the invention is the novel 20 pawl and ratchet means employed for imparting the step-by-step movement to the advertising band, there being novel means employed for transmitting motion from the 25 tiltable platform to the pawl and ratchet means so that an exceedingly slight movement of the platform will serve to impart the necessary degree of rotation to the band to bring up a new sign each time the 30 platform is depressed.

Another feature of the invention is the 35 rotatably mounted calibrated discs serving to display the various weights, together with characteristic means operated from conventional mechanism in the hollow tiltable platform.

Other features and advantages of the 40 invention will become apparent from the following description and drawings.

In the accompanying drawings forming 45 a part of this application and in which like numerals are employed to designate like parts throughout the same:

Figure 1 is a front elevation of a weighing 50 scale constructed in accordance with the present invention.

Figure 2 is a top plan view of the same.

Figure 3 is a side view showing the housing in section and portions therein in elevation.

Figure 4 is a sectional and elevational view showing the power multiplying means and scale operating means more clearly.

Figure 5 is an enlarged detail view of one 55 end portion of the advertising band drum.

Figure 6 is a fragmentary detail view of a portion of the advertising band.

Referring to the drawings in detail, the reference character 1 designates a base from which a standard 2 rises. The standard is 60 rigidly connected with an upstanding vertically elongated housing 3. The housing is substantially rectangular in configuration, being relatively narrow at the top and widened somewhat at the bottom. Formed 65 in the narrowed top is a glass window 4. Formed in the portion providing the junction between the upper and lower portions is a sight opening 5 through which the different weight numbers may be clearly 70 viewed. Mounted for rotation at the top of the housing is a plane surfaced drum 6. Mounted for rotation at the bottom is a complementary drum 7, the last named drum being 75 provided adjacent one end with a circumferential row of projections 8. A flexible fabric band or its equivalent 9 of endless form is trained over these drums. As shown in Figure 7 one edge of the band is 80 provided with a multiplicity of perforations 10, and the projections 8 on the lower drum 7 extend through these perforations. In this way, rotation of the drum 7 serves to impart movement to the band. Obviously the band is 85 divided into a plurality of display areas 11, each one of which carries a different advertisement. The area is preferably of a size corresponding with the window 4 and is adapted to be brought opposite this window to permit it to be plainly seen when the scale is operated. Directing attention to Figure 5, it will be noted that a ratchet 12 is mounted for idling movement upon the journal at this end of the drum. The ratchet embodies a flanged hub 13 to which 90 one end of a coiled spring 14 is connected. The spring is anchored to the housing at its opposite end, and obviously serves to rotate the ratchet and hub in a direction from left to right and to maintain and automatically return the ratchet to its normal position after each operation. A bracket 15 is 95 mounted in the housing, and a relatively short belt 16 is passed over a pulley carried by this bracket, the free end of the belt being anchored upon the hub 13, and the opposite end being connected to the front wall of the enlarged lower wall of the housing.

That portion of the belt between the pulley 100 bracket and the last named end is passed 110

over a freely rotatable pulley 17 on the free end portion of a rockably mounted lever 18 confined in the housing. From Figure 4 it will be noted that this lever 18 is pivoted at 5 a point between its center and one end. Also, a link 19 is connected to the short end, and depends through an opening in the bottom of the housing and is connected to a bracket 20 in the hollow platform 21. The 10 platform is provided with spaced ears 22 which straddle and are pivotally connected to the aforesaid standard 2. A spring 23 is interposed between the platform and the standard to maintain the platform normally 15 in a substantially horizontal plane with its upper side in contact with the bottom of the housing 3 as shown plainly in Figure 3.

That portion of the platform 21 projecting beyond the bottom of the housing and 20 overlying the base 1 is formed in its top with an opening through which a depressible circular plate 24 is movable. It is upon the plate 24 that the occupant of the scale is adapted to stand. In this connection, it is 25 to be pointed out that the platform is such as to accommodate conventional mechanism for exerting a downward pull on the vertically extending rod 25 when the plate is depressed. The rod 25 extends through an 30 opening in the bottom of the housing 3 upwardly and into the housing. On the upper end thereof is a toothed rack bar 26, the teeth of which mesh with a pinion 27 keyed upon the front face of a rotary scale disc 28. 35 The disc 28 occupies a considerable portion of the lower part of the housing and the periphery thereof is graduated in the customary way to indicate the various degrees of weight from zero on. The periphery is 40 positioned directly beneath the aforesaid sight opening 5, so that the occupant may look down through the sight opening to observe the particular weight given. Attention is directed to Figure 4, wherein it will 45 be seen that an arm 29 is pivoted between its ends and is provided at one end with a threaded portion carrying an adjusting weight 30. The opposite end of the arm is connected through the medium of the link 50 31 to the intermediate portion of the aforesaid rod 25. The central hub of the arm 29 carries an angularly disposed extension 32 upon which a relatively larger weight 33 is mounted. It is clear that the weighted arm 29 constitutes an adjusting means by 55 which the mechanisms may be equalized to dispose the zero mark on the scale in the true starting position.

Considering first the operation of the advertising means, it will be seen that each time the platform 21 is occupied, it will swing downwardly upon its pivot and against the action of the coil spring 23. In so doing, it will exert a downward pull on 60 the short end of the lever 18 through the me-

dium of the link 19. This will lift up upon the pulley 17 at the free end of the lever, and the pulley will exert a pressure upon the short belt 16. This belt when under stress 70 serves to impart rotation to the ratchet 12 through the medium of the hub 13 which is connected thereto. In this connection it should be observed from Figure 3 that the aforesaid drum 7 carries a spring pressed pawl 34 which is engageable with the teeth 75 of the ratchet. Obviously then, as the ratchet is rotated in a direction from right to left, it will impart rotation to the drum 7, and the drum in turn will turn the advertising band 9 through a predetermined distance to bring one of the display areas 11 80 opposite the window 4. After the occupant steps off of the platform, it will resume its normal horizontal position under the action of the spring 23, and the ratchet 12 will be returned automatically to its normal position through the medium of the spring 14, it being remembered that the ratchet is 85 mounted for idling upon the journal of the drum. In this way the advertising band 90 will be moved around in a step-by-step manner, and as each person steps on the platform, a new sign will be brought up for display.

Considering the operation of the scale itself it is clear that as the plate 24 is depressed, it exerts a downward pull upon the rod 25, which through the medium of the rack and pinion imparts rotation to the scale disc 28. As before stated, conventional mechanism is located in the hollow platform 21 for cooperation with the rod 25 to bring about the proper proportion of movement to turn the scale disc the desired degree.

The weighing scale mechanism herein 105 specifically described and shown, being a divisional subject matter, is not herein claimed, but is embodied and claimed in a separate divisional application filed by me on August 27, 1925, and bearing Serial No. 52,806. Accordingly, the novelty herein alleged is restricted to what may be conveniently designated as the advertising mechanism.

Undoubtedly, by considering the description in connection with the drawings, persons skilled in the art to which the invention relates will be able to obtain a clear understanding of the same. Therefore, a more lengthy description is thought unnecessary.

While the preferred embodiment of the invention has been shown and described, it is to be understood that minor changes coming within the field of invention claimed may be resorted to if desired.

Having thus described the invention, what I claim as new and desire to secure by Letters Patent is:—

In a structure of the class described, a vertically elongated housing provided in its

front with a window, drums mounted for rotation in said housing, an endless advertising band trained over said drums, a pawl carried by one of said drums, a ratchet mounted for idling, the teeth of said ratchet being engageable with said pawl for imparting rotation to said one drum, a flexible element anchored at one end upon said ratchet for imparting rotation thereto, the 10 opposite end of said element being anchored upon a relatively stationary part, a lever pivotally mounted between its ends upon said housing, a pulley carried by the free end of the lever and cooperable with said flexible element, a tiltable platform, and a 15 connection between the platform and the opposite end of said lever.

In testimony whereof I affix my signature.

PHILIP VIVIANO.
